MERCANDISE CONTAINER

Reynolds Guyer, St. Paul, Minn., assignor to Wal-
dorf Paper Products Company, St. Paul, Minn.,
a corporation of Minnesota

Application June 18, 1941, Serial No. 398,619

6 Claims. (Cl. 206—44)

My invention relates to an improvement in merchandise containers, wherein it is desired to provide a means for stiffening fibrous board to render the same capable of maintaining shape when containing articles of merchandise.

Various types of containers have been used for the packing of fragile articles to be shipped. Corrugated paper board has been commonly used for enclosing the articles during transportation. This corrugated paper board is possessed of considerable stiffness when in its flat state. However, when this board is folded across the corrugations, the rigidity of the board along this line is destroyed. If such material is folded into box formation, some means must be provided for locking the various walls of the box together, as otherwise the box would unfold along the various fold lines. It would be extremely advantageous if two sections of corrugated paper board, connected along a fold line intersecting the corrugations, would maintain a set relationship. The packing of merchandise could then be greatly simplified.

The object of the present invention is to provide a stiffening means within the fibrous board which will resist folding of the board at the fold lines. With such an arrangement, no locking tongues, fastening means, or binding devices are necessary to hold the folded sections in desired angularity. As a result, merchandise may simply be placed in a support such as a channel shaped tray, and the upper edges of the channel folded partially over the merchandise, holding the same firmly wrapped. At the same time, such channels may be open throughout a major portion of the area of the top, permitting the display of the goods packed.

It is an object of the present invention to provide a means of stiffening the lines of fold of fibrous board containers, so as to thoroughly protect the merchandise and at the same time to leave the merchandise openly visible for display. As a result, the goods may remain in packed condition until sold to a customer. Two advantages exist in such a construction. In the first place, it is not necessary for the store owner to remove the goods from their original packing for display purposes. In the second place, it is not necessary for the store owner to pack the merchandise for delivery to the customer. Both of these advantages means the saving of time and money to the merchandiser.

An extremely important features of the present invention lies in the ease with which merchandise containers may be manufactured and assembled. In the formation of the containers, it

is only necessary to blank out the container body to the desired shape, and with the fold lines properly scored; and to subsequently insert between the corrugations a ductile or malleable stiffening means so as to extend on both sides of the lines of fold. In the assembling of the containers, it is only necessary to bend the sections of the container along the fold lines. The ductile stiffening means will bend to assume the proper folded shape. However, when once bent, the sections of the container will remain in the same angular relationship until sufficient force is exerted to change the angle of bend of the ductile stiffener. The sections are then sustained without the use of separate fastening means.

A feature of the present invention resides in the fact that the ductile stiffening means may, if desired, project from the ends of the container sections through which it extends, providing a means of holding or supporting elements of merchandise contained. As a result, the stiffening means may form not only a means for holding the folded sections of the container in the desired relationship, but also an attaching means for holding the merchandise in set relationship with respect to the container.

These and other objects and novel features of my invention will be more clearly and fully set forth in the following specification and claims.

In the drawings forming a part of my specification:

Figure 1 is a perspective view of a display container enclosing merchandise to be shipped and displayed.

Figure 2 is a plan view showing the died-out formation of one of the sections of the enclosing container.

Figure 3 is a plan view showing the died-out formation of the other section of the enclosing container.

Figure 4 is a perspective view of a packing support for merchandise, showing the merchandise contained therein.

Figure 5 is a perspective view of the packing support for merchandise illustrated in Figure 4, showing the merchandise removed therefrom.

Figure 6 is a perspective view of an auxiliary part of the specific merchandise packing support illustrated in Figure 4.

Figure 7 is a plan view of the died-out formation of the packing support illustrated in Figure 5.

Figure 8 is a cross-sectional view through the corrugated paper board and the stiffening member enclosed therein.

Figure 9 is a perspective view of a modified

form of support, and display container used in conjunction therewith.

Figure 10 is a perspective view of the merchandise support illustrated in Figure 9, with the merchandise removed therefrom.

Figure 11 is a plan view of the died-out formation of the merchandise support illustrated in Figure 10.

Figure 12 is a cross-sectional view through the corrugated paper board and the stiffening element embodied therein.

My invention is applicable to a great number of different specific forms of construction; and for this reason the embodiments illustrated are only indicative of the manner of carrying out the invention. The specific shape and form of the container must to some degree be dependent upon the type of goods to be shipped and displayed.

The display container A, illustrated in Figures 1, 2, and 3 of the drawings, is designed to accommodate fragile goods such as the so-called hurricane lamps B. The container A as illustrated comprises a base 10, and a pair of end walls 11 and 12, secured to the base 10 along the fold lines 13 and 14, respectively. The end walls 11 and 12 are generally rectangular in shape, and comprise two sections connected along a fold line. The end wall 11 comprises a lower section 15 connected to the base 10 along the fold line 13, and connected to the upper section 16 along the diagonal fold line 17. The end wall 12 comprises a lower section 19 connected along the fold line 14 to the base, and connected to the upper section 20 along the diagonal fold line 21. The upper end wall sections 16 and 20 may fold out from the end walls as seen in Figure 1, to better display the merchandise.

As best illustrated in Figure 2 of the drawings, a ductile or malleable stiffening means, in the form of a wire rod 22, extends between corrugations of the board from which the container is formed, extending through the fold lines 13, 14, 17, and 21. The manner in which the stiffening means 22 is positioned is best illustrated in Figure 8 of the drawings. The board from which the container A is formed comprises a pair of spaced parallel covering sheets 23 and 24, with a corrugated web 25 connecting the same and connected along the ridges of the corrugations to the sheets 23 and 24. Spaced parallel passages are thus formed by the web 25, through which the wire 22 may extend.

A second container section is shown in Figure 3 of the drawings. This section comprises a container rear panel 26, connected along the fold line 27 to the container top 29. The top 29 is connected along the fold line 30 to the container front wall 31. The top 29 is formed of a display panel section 32, which is separated from the rear supporting portion 33 by a substantially U-shaped line of separation 34. Fold lines 35 connect the display panel section 32 with the rear supporting section 33, so that the display panel section may be erected into the display position illustrated in Figure 1 of the drawings, or the entire top panel 29 may extend in a common plane.

A pair of stiffening wires 36 are inserted between the corrugations of the web connecting the covering sheets of the corrugated board, as illustrated in Figure 8. These ductile or malleable wires 36 extend through the fold lines 27, 30, and 35. Thus when this section is folded into the display position illustrated, the parts are held

in proper relationship by these stiffening elements 36. The rear panel 26 is taped or otherwise secured to the end walls 11 and 12, and to the base 10, in the assembled container.

5 The hurricane lamps B are individually contained in supports C designed to protect the lamps and to hold the same in proper relationship. The hurricane lamps B comprise a dish-like holder 37, designed to support a candle 39, and also a lamp chimney 40. As both the lamp chimney and the holder are formed of fragile material, it is necessary to hold these elements in spaced relation, and also spaced from similar elements of other lamps B.

10 The supports C comprise a base 41 formed of corrugated paper board, connected along fold lines 42 to side walls 43, which, in turn, are connected to the flanges 44 along the fold lines 45. The corrugations of the connecting web within 15 the corrugated board extend at substantially right angles to the fold lines 42 and 45, so that these fold lines intersect the corrugations. A ductile or malleable stiffening element 46 extends longitudinally of the web corrugations, and 20 the ends 47 of the stiffening element project beyond the ends of the flanges 44, as best illustrated 25 in Figures 5 and 7 of the drawings.

The supports C are formed into the shape illustrated in Figure 5 of the drawings, the base 41 30 and side walls 43 forming a channel-shaped tray, and the flanges 44 extending inwardly from the side walls 43, extending substantially parallel to the base 41. The projecting ends 47 of the stiffening element 46 are bent upwardly, and are outwardly kinked at 49, to engage the inner walls of 35 the lamp chimney which is subsequently supported thereby.

A disc 50 having a central aperture 51 and oppositely disposed notches 52 is applied over the flanges 44, the notches 52 straddling the upstanding wire ends 47. A pair of opposed ears 53 are bent up from the body of the disc 50 to engage within the lamp chimney 40 to hold the same centered. The dish-shaped holder 37 rests upon 40 the support base 41. The candle 39 extends through the aperture 51 in the disc 50, and is supported by the holder 37; the disc 50 thus acting through the candle 39 to hold the holder 37 in place. The lamp chimney 40 is supported 45 by the disc 50, and held upright and centered by the ears 53, and is frictionally engaged by the ends 47 of the stiffening element, the kinks 49 engaging in the outwardly bulged portion 54 of the chimney 40.

50 In packing the lamps B in the container A, the supports C of alternate lamps are turned at right angles, so that in the finished container the holders 37 are all confined within four upstanding walls arranged in a square. Thus, during transportation, the holders 37 of the lamps B cannot move out of proper position.

55 In Figures 9 through 12 of the drawings, I disclose a modified form of construction of container. In this form, the outer packing container D is in the general form of a box of rectangular shape, including a base (not shown), a front wall 55, a rear wall 56, and opposed side walls 57. Short cover flaps 59 are secured along fold lines 60 to the side walls 57. A top panel 61 is connected along the fold line 62 to the front wall 55, and a rear panel 53 is secured to the rear wall 56 along the fold line 63. If desired, a ductile stiffening element 64 may be embedded within the rear panel 56, extending on both sides of

the fold line 63 so as to make this rear panel self sustaining.

Custard cups E are shown as the specific merchandise packed within the container D; and these fragile cups are held in proper relation by a merchandise support F. This merchandise support acts to hold the cups spaced, and holds them contained in units, each supporting four cups.

The supports F comprise a base 65 having apertures 66 through which the tapered walls of the cups E may extend and engage. These apertures are of such a size as to hold the mouths of the cups spaced well above the base 65; but sufficient of the cup extends through the apertures to securely hold the cups in fixed relation.

Connected along fold lines 67 to the base 65, I provide side walls 69. These side walls extend upwardly from the base 65 at substantially right angles thereto; and combine with the base to form a channel-shaped tray. Spaced flanges 70 are secured to the upper edge of the side walls 69 along fold lines 71. Each of the flanges 70 engages the top surface of two adjacent cups E, to hold these cups in place upon the base 65. Opposed pairs of the flanges 70 engage the cups. Arcuate notches 72 are formed in the flanges 70 so that these flanges engage or overlie the rims of the cups, but do not conceal the interior portion of the cups.

Ductile or malleable stiffening elements 73 extend through the flanges 70, side walls 69, and base 65 of the supports F to stiffen the fold lines in the corrugated paper board supports. The fold lines 67 and 71 extend transversely of the direction of the corrugations, and accordingly the stiffness of the board is destroyed along the line of fold. The bendable wires 73 are inserted between the corrugations of the web within the board, as best illustrated in Figure 12 of the drawings, this corrugated web being indicated by the numeral 74, and the covering sheets being designated by the numerals 75 and 76.

Obviously, the corrugated paper board will not remain in any set position along the lines of fold unless stiffened by some such means as is provided by the applicant. However, with such a stiffening element in place, the flanges 70 act to hold the cups E in position, and the four cups mounted on each base 65 may be handled as a unit. As the material forming the stiffening elements such as 73 is ductile and malleable, it will retain the shape into which it is manually set, and resists bending along any of the fold lines through which it extends.

When the container D is opened into display position, it is desirable to hold the cups E prominently displayed. To accomplish this end, I provide apertures 77 in the front display panel 61, which apertures register with the apertures 66 in the base 65 of the support F. The lower ends of the cups E which project below the base 65 engage in these apertures, so that the base 65 may rest directly upon the inclined panel 61 in inclined display position.

The simplicity of assembly of such containers makes them extremely desirable for use in holding merchandise while it is shipped and displayed. To hold the merchandise in position, it is only necessary to fold the supporting tray in position to enclose the same sufficiently to prevent removal of the same. The stiffening element prevents the unfolding of the tray out of this engaging position.

In constructing the merchandise container the blanks are cut out in the proper form and the fold lines scored or creased into the blanks. This scoring or creasing at the fold lines acts to bend the corrugations so as to destroy the stiffness of the board along the line of fold. After creasing, the stiffening wires are inserted to extend through the lines of fold, to reinforce the fold lines.

10 In accordance with the patent statutes, I have described the principles of construction and operation of my merchandise container, and while I have endeavored to set forth the best embodiments thereof, I desire to have it understood that these are only illustrative of a means of carrying out my invention, and that obvious changes may be made within the scope of the following claims without departing from the spirit of my invention.

15 I claim:

1. A merchandise packing support comprising a base, and a retaining flap means foldably secured thereto along a fold line and designed to engage an article of merchandise upon said base, said base and flap means being formed of a sheet of corrugated paper board comprising a pair of spaced parallel covering sheets and a connecting corrugated web forming passages through the board, and a ductile stiffening element extending within one of said passages beyond the line of fold to render the board resistant to bending at the fold line, said ductile element projecting from the flap means to engage the article of merchandise to hold the article in fixed relation to said base.

2. A merchandising packing support comprising a base, opposed flap means foldably secured to said base along fold lines, said base and flap means being formed of corrugated paper board comprising a pair of parallel spaced covering sheets connected by a corrugated web, providing passages through the board between the corrugations, and a ductile stiffening means extending through one of said passages and extending 45 beyond the ends of said flap means, the corrugations of said board extending across the lines of fold, the ends of said ductile means being exposed for engagement with an article of merchandise to hold the article in fixed relation to 50 said base.

3. A merchandise packing support in combination with an article of merchandise comprising a channel-shaped tray having a base and foldably connected side walls of corrugated paper board, the article engaging said base between said side walls, the corrugations of the paper board extending transversely of the channel and forming passages through the board intersecting the fold lines connecting said base to said side walls, flanges foldably connected to the free edges of said side walls and foldable into opposed spaced relationship to engage opposite portions of the article engaging said base, and a ductile stiffening element extending through one of said passages and extending on both sides of said fold lines, said ductile stiffening element holding said flanges in engagement with opposite sides of said article of merchandise to hold said article against said base.

4. A merchandise packing support in combination with an article of merchandise, comprising a channel-shaped tray having a base and foldably connected side walls, flanges foldably connected to the upper extremities of said side walls, 75 said article engaging against the base, said flanges

engaging spaced marginal edges of said article to hold said article in engagement with said base, said packing support being formed of a single sheet of corrugated paper board, the corrugations of which extend transversely of the channel to form passages through the flanges, side walls, channel base, and a ductile stiffening element extending through one of said passages and extending on both sides of the line of fold, said ductile stiffening element holding said flanges firmly against the upper extremity of the article of merchandise to clamp the same against said base.

5. A merchandise packing support in combination with an article of merchandise, comprising a channel-shaped tray having a base and foldably connected side walls, opposite spaced flanges on said side walls foldable substantially into alignment and being maintained in spaced relationship, said channel shaped tray and flanges being formed of a single piece of corrugated paper board, the corrugations of which extend transversely of the channel to provide passages through the board intersecting the fold lines thereof, and ductile stiffening element extending through one of said passages provided on both

sides of each of the lines of fold in said corrugated paper board, said stiffening element acting to hold said article against said base, means on said base for holding the article of merchandise from lateral movement in any direction, said flanges engaging over opposed edges of said article of merchandise to hold the same from movement away from said base.

6. A merchandise packing support in combination with an article of merchandise, comprising a base, flaps foldably connected to said base along substantially parallel fold lines, said flaps engaging over opposed marginal portions of the article of merchandise and being arranged in spaced relationship to display the article of merchandise between said flaps, said base and flaps being formed of a single sheet of corrugated board having the corrugations thereof intersecting said fold lines at substantially right angles, and a ductile stiffening element in one of said corrugations extending on both sides of both of said fold lines to hold said flaps clamped against said article of merchandise to hold the article of merchandise against said base.

25

REYNOLDS GUYER.
